ATTORNEYS

UNITED STATES PATENT OFFICE.

BENJAMIN DAY, OF WEST HOBOKEN, NEW JERSEY.

DESIGN FOR A PRINTING-FILM.

SPECIFICATION forming part of Design No. 34,331, dated April 2, 1901.

Application filed March 7, 1901. Serial No. 50,270. Term of patent 14 years.

To all whom it may concern:

Be it known that I, BENJAMIN DAY, a citizen of the United States, and a resident of West Hoboken, in the county of Hudson and State of New Jersey, have invented and produced a new and original Design for a Printing-Film, of which the following is a full, clear, and exact description.

Reference is to be had to the accompanying drawings, forming a part of this specification, in which—

Figures 1 and 2 are plans of a film, exhibiting my new design, the letters *a a* indicating the junction-line of the two figures.

The leading feature of my design consists in a printing-film having the particular irregular

arrangement of dots shown in the drawings, with the dots closer together in certain portions than in others, so as to present a graded effect or shading.

Having thus described my invention, I claim as new and desire to secure by Letters Patent—

The design for a printing-film, as herein shown and described.

In testimony whereof I have signed my name to this specification in the presence of two subscribing witnesses.

BENJAMIN DAY.

Witnesses:

BENJ. H. DAY,
SYDNEY FISK.
